UNITED STATES PATENT OFFICE.

WILLIAM McCLOVE, OF SCRANTON, PENNSYLVANIA, ASSIGNOR TO
McCLOVE-BROOKS COMPANY, A CORPORATION OF PENNSYLVANIA.

GRATE.

No. 831,178.

Specification of Letters Patent.

Patented Sept. 18, 1903.

Application filed November 4, 1905. Serial No. 285,900.

To all whom it may concern:

Be it known that I, WILLIAM McCLOVE, a citizen of the United States, residing at Scranton, in the county of Lackawanna and State 5 of Pennsylvania, have invented certain new and useful Improvements in Grates; and I do hereby declare the following to be a full, clear, and exact description of the invention, such as will enable others skilled in the art to 10 which it appertains to make and use the same.

This invention relates to improvements in grates, and particularly to rocking grates, which are pivotally mounted or journaled in 15 a combustion-chamber of a furnace in such a manner that they are capable of being rocked for dumping the material thereon into the ash-pit.

It is the object of the invention to provide 20 a grate in which rocking bars may be used, the said bars tipping only in one direction for dumping materials from the grate-surface, their edges being so shaped as to be capable 25 of moving one upon the other to some extent to permit of the expansion of the bars under great heat and yet not interfere with their 30 being rocked for dumping the materials into the ash-pit, nor to materially interfere with the free use of firemen's cleaning implements, such as slash-bars, hoes, &c., when in normal position.

It is the further object of the invention to 35 provide a rocking grate-bar with fuel-supporting portions or caps having noses which match and fit upon the noses of adjacent caps to prevent the running through of fuel and to provide means for rocking the bars in 40 one direction and adjustable means for controlling the return of the bars and prevent them from pounding one upon the other.

With these and further objects in view the 45 invention comprises certain novel constructions, combinations, and arrangements of parts, as will be hereinafter fully described and claimed.

In the accompanying drawings, Figure 1 is 50 a vertical sectional view through the combustion-chamber of the furnace, showing my improved grate mechanism applied therein, the bars of one section thereof being rocked to their dumping positions. Fig. 2 is a top plan view of a portion of the grate-surface, showing parts of adjacent grate-bar caps.

Fig. 3 is an enlarged vertical sectional view through adjacent bars and their fuel-supporting caps. Fig. 4 is a detail view showing the noses of adjacent caps formed with inclined faces. Fig. 5 is a similar view, but showing the noses of the cap rounded where they lap one upon the other. Fig. 6 is a similar view, 60 but showing the caps riding slightly upon each other, as where they have been expanded and forced together when not controlled by the adjustable controlling means on the boiler-front. Fig. 7 is a similar view, but showing 65 the caps expanded by heat, but so adjusted by the controlling means that the bars cannot strike each other and that an air-space will be maintained between the edges of the caps. Fig. 8 is a detail view showing adjacent edges of grate-bars, the said edges having lapping faces arranged in approximately 70 horizontal planes. Fig. 9 is a detail sectional view showing the set-screws for engaging the stub-levers.

The present invention is designed principally for use in the burning of exceedingly fine anthracite fuels and for that reason is composed of rocking grate-bars formed with quite small mesh, so that very fine anthracite fuels cannot run through the same. For the same reason the bars are made with a very small space between the rocking portions.

Rocking grate-bars have usually been made so that they can rock in both directions, and 85 this is found useful in handling soft or bituminous coal and anthracite coals, except the very smallest grades. In forming a rocking grate for the fuels commonly in use it is generally sufficient to bring the edges of the adjacent bars within a quarter of an inch of each other, and the fuel will not run through. When, however, the very small grades of anthracite fuel are burned upon the grate, an opening of the size of a quarter of an inch is 90 usually too large and will militate against the general efficiency of the whole grate, principally because small coal sifts through between the bars, and where a forced draft is used the air rushes through these lines of least resistance with such force as to tear a bed of small anthracite fuel badly. In meeting these difficulties and in supplying the need for the grate upon which very small anthracite fuel can be burned to advantage, I 95 provide a rocking dump-grate in which the

bars are capable of rocking only a certain distance—that is, sufficiently far to dump the ashes and clinker, after which they are brought to a level again. By constructing these bars so that they can rock in only one direction the mesh or space between them can be reduced to a minimum without detriment to the furnace and by my invention in such a manner that no obstruction will be offered to a hoe when moving the fuel from one part of the grate to another.

In the accompanying illustration I have shown a grate mechanism embodying the features of my invention, in which 1 indicates 15 grate-bars which are journaled at their ends in the furnace structure in any desired manner, (usually in journal-bearing bars,) and each of said bars is provided with a socketed body portion 2. The said body portions 2 carry fuel-supporting portions, which I shall term "caps," as 3, the said caps having downwardly-projecting shanks 4, which fit into the sockets in the body portion 2, as clearly shown in Figs. 1 and 3. The said caps are 25 formed with a head 5 and lateral projecting web portions 6, which have laterally-extending teeth 7, as clearly shown in Figs. 2 and 3. The outer ends of the webs 6 are connected by a tie portion 8, and projecting beyond said 30 tie portion 8 are teeth or projections 9 and 10. The teeth 9 at one end of the bar are arranged upon a higher point of the tie portions 8 than the teeth 10 at the other end of the cap, so that when the adjacent ends of caps upon adjacent bars meet, as shown in Fig. 3, the teeth 9 will lap upon and overhang the teeth 10. The formation of the teeth 9 and 10 and the upper surface of the tie-bars adjacent thereto is important, since it permits of the 40 grate-bars being placed sufficiently close together to secure a space or mesh between them, through which fine anthracite fuel cannot sift or run, and yet thelapping of the teeth is such that the bars may be rocked 45 in one direction for dumping ashes from their fuel-supporting surfaces into the ash-pit below. The under surfaces of the teeth 9 upon one bar are usually made parallel with the other upper surfaces of the adjacent teeth 10 50 on the next bar, so that the teeth may be brought quite close together and yet leave a small space with parallel walls between them, as clearly shown in Figs. 3 and 4. As shown in Figs. 3, 5, and 6, the upper edges of the tie 55 portions 8 may be rounded or curved to facilitate the drawing of the hoe or other movement over the surface of the grate. The curved surfaces and the upper surfaces of the teeth 9 form slight depressions between the 60 adjacent caps of adjacent bars over which the hoe or other implement may be easily drawn in shifting the fuel upon the grate-surface. It will be observed that when the caps are thus formed and fitted at the edge with 65 respect to each other the extension and

growth of the caps, due to the continued use when exposed to excessive heat, permits of the ends of the caps approaching each other closer and closer without interfering with the movement of the bars or with the pulling of the hoe over the grate-surface. The bars may even expand until the teeth 9 and 10 engage each other and are, in fact, partially shoved one upon the other, as shown in Figs. 5 and 6. This expansion may be even accommodated 75 until the caps of the bars cannot be brought to their perfect horizontal alinement, as when originally placed in the grate. This is indicated by the position of the caps shown in Fig. 6 with relation to the original grate-surface, as indicated by the dotted line. Even in this position it will be observed that the meeting edges of the caps afford no obstruction or projection upon the grate-surface over which the hoe cannot be drawn for moving the fuel from place to place, and it will also be observed that the grate-bars may still be tipped or rocked with respect to each other for dumping the ashes.

Instead of rounding the upper edges of the tie portions 8 they may be made with corners, the upper inclined faces of the teeth being extended to meet more or less sharply the upper surface of the caps. This formation will permit of the advantages above stated with respect to the caps shown in Figs. 3 and 6. As shown in Fig. 5, a similar result may be obtained by forming the upper surface of the tie portions 11 and 12 of adjacent caps with rounded surfaces and by forming teeth 13 and 14 with curved under surfaces, the under surfaces of the teeth 13 being made to fit closely upon the curve of the upper portion of the teeth 14 and of the tie-bar 12 in the event of the caps becoming sufficiently expanded to drive the parts together. While of course the tie-bars 8 and 11 and 12 might be extended in the place of the teeth 9, 10, 13, and 14, it is preferable to form the teeth upon the said tie-bars by means of the kerfs or slots 15. (Shown in the end edges of the caps in Fig. 2.) This not only serves to break up what would otherwise be a double line of metal, one near to the other, exposed to the heat at the cap edges, but also affords sufficient opportunity for air to pass upwardly through the end portions of the caps, even when they are driven upon each other, as illustrated in Figs. 5 and 6.

As shown in Fig. 8, thelapping surfaces of the edges of the bars may be arranged in approximately horizontal planes. As shown in this view, the adjacent edges of the fuel-supporting portions of the bars are depressed by curving or rounding them downwardly, as at 27 and 28. Extending beyond the rounded depressed portion 27 of one bar at one edge is a projection 29, having a horizontal upper surface 30. The adjacent edge of the next bar is formed with a horizontal lap-

ping surface 31 beneath the depressed rounded portion 28. The arrangement of the meeting edges of the bars is thus such that they may grow toward each other under the expansion produced by exposure to severe heat and at the same time the depressed edges 27 and 28 will make it possible to employ the usual firemen's implements in moving or arranging the fuel upon the grate-surface without difficulty. It will be seen that the overlapping portions of the bars do not interfere with the rocking of the bar and that by making the horizontal faces 30 and 31 of a suitable length and only lapping them to a slight degree when the bars are new that the bars may be expanded to a considerable extent without causing any binding action between the parts. Although a bar of this character is substantially like those shown in the other views of the drawings, I preferably use the bars with inclined lapping edges, as above described.

Each of the bars 1 is provided with a downwardly-projecting arm 16, which is pivotally connected with a link, as 17, and the bars are usually connected by such links, as 17, in groups, as shown in Fig. 1, so that different sections of the grate-surface may be rocked for dumping the ashes at different times. As shown in Fig. 1, the front section of the grate is rocked for dumping the ashes, while the rear section is held in its normal position for supporting fuel. In cleaning and changing fuel and getting rid of the ashes upon a grate of this character the good fuel is usually pushed upon one of the grate-sections—as, for instance, the rear grate-section—and the front grate-section is then dumped for depositing all of the ashes and clinkers into the ash-pit. The front section is then restored to its normal position and the unconsumed fuel on the rear section is drawn upon the front section by a hoe or other implement, and the rear section is then rocked for depositing the ashes in the ash-pit. After this operation has been completed and the grate-bars have all been restored to their normal approximately horizontal positions the fuel is then again evenly spread over the grate-surface, and new fuel, if required, is supplied. In rocking the grates the links 17 are actuated by rods 18 and 19, one running to one section of the grate, while the other runs to the other section. The forward ends of the said rods 18 and 19 extend through the furnace-front 20 and are connected to stub-levers 21 and 22. The said stub-levers are fulcrumed upon pivot-links 23, mounted upon the furnace-front, and their upper ends are adapted to be engaged by an operating lever or handle 24, which is capable of fitting upon the ends of one or both of the stub-levers.

Although the bars, as thus far described, may be employed without adjusting means

and will be effective for accommodating the expansion of the parts under the action of heat without interfering with the movement of hoes or other firemen's implements over the grate-surface, yet it is preferable to provide means by which the grate-bars may be limited in their movement toward each other when returning them to their normal positions. In order to coöperate with the movement of the grate-bars and to be able to adjust the distance between their meeting edges when in a normal position, I employ set-screws, as 25. The said set-screws are adjusted so that the stub-levers 21 and 22 will strike against them in their rearward movement, and the said levers will thus be limited in the extent of their movement when bringing the bars to their normal position. It will be readily understood that by adjusting the screw 25 outwardly to a slight extent the bars may be prevented from rocking sufficiently to bring their meeting and overlapping edges together, and the space or crevice between such meeting edges can thus be increased or diminished in accordance with the adjustment of said screw 25. A binding-nut 26 is usually provided for each screw, so as to hold the screw against accidental turning when not being adjusted. The screws 25 make it possible to still prevent the touching of the grate-bars after the caps have expanded and grown sufficiently to touch and ride one upon the other if left to their original adjustment. Thus when the bars have expanded under continued use, as shown in Fig. 6, by adjusting the screws 25 outwardly to a slight extent the overlapping fingers may be prevented from quite touching when the bars are rocked to their approximately horizontal position. This is advantageous, since it prevents the striking of the bars against each other with hard blows, which might result in the breaking of the bars or their caps, especially after they have become expanded from exposure to the excessive heat. In this manner also a small space may always be maintained between the adjacent and overlapping ends or teeth of the caps to permit of a small feed of air at that point, which not only assists in the even distribution of air for combustion, but maintains the parts of the grate-bars and their caps at a slightly cooler temperature than if they were permitted to rest one upon the other.

In forming a grate with bars as above described, which are not intended for rocking in both directions, I find that the caps of these bars may be made longer than they are usually made when the bars are rocked in both directions. Thus instead of making the length of a cap, which of course is the same as the width of the fuel-bearing surface of the bar, about six inches, such a cap may be made twelve inches in length. This reduces the number of bars which it is necessary to em-

ploy in a grate-surface and also lightens the structure of the grate, since a less number of body portions have to be supplied and journaled in the grate structure. The structure of the grate is exceedingly simple, and yet the mesh or air-feeding spaces formed in the grate-surface may be reduced to any size necessary for handling the smallest grades of anthracite fuel.

10 Having now described my invention, what I claim as new, and desire to secure by Letters Patent, is—

15 1. A grate having a fuel-bearing surface composed of caps formed with double-beveled edges, the said double bevel permitting of the movement of one edge over the other in the expansion of the grate-bars.

20 2. A grate mechanism, comprising rocking bars provided with depending edges adapted to overlap the edges of adjacent bars, the meeting-point of said edges being below the grate-surface.

25 3. A grate mechanism, comprising rocking bars, formed with fuel-supporting caps, the meeting edges of said caps being inclined to lap one upon the other and ride upon each other when expanded under the action of heat and depressed portions formed at said edges to permit of the lapping of the caps and 30 yet not offer obstruction to the movement of implements upon the grate.

35 4. A grate mechanism, comprising rocking grate-bars having fuel-supporting caps and projecting teeth at the edges of said caps capable of lapping upon the caps of the adjacent bar, the said lapping portion having an inclined face opposed to the surface of the adjacent bar.

40 5. A grate mechanism, composed of rocking grate-bars having fuel-supporting caps, the edges of said caps being inclined downwardly from the upper surface thereof and inclined teeth formed upon the edge of said caps for maintaining proper air-spaces between the edges of adjacent bars.

45 6. A grate mechanism, comprising rocking grate-bars having fuel-supporting caps, beveled downwardly at their edges from the top surface, one edge of each cap extending downwardly to a greater extent than the other edge, so that adjacent edges of the bars may lap upon each other, the lapping of the bars permitting of the expansion of the caps under the action of heat without making large initial spaces between the caps, and without offering obstruction to the movement of fuel upon the grate-surface, when in normal position.

50 7. A grate mechanism, comprising rocking grate-bars having fuel-supporting caps, the edges of the caps being depressed and inclined at an angle with respect to the fuel-surface of the cap and lapping projections carried by the edges of the caps having inclined meeting surfaces for facilitating the

riding of one cap upon the other upon the expansion of the said caps under the action of heat.

55 8. A grate mechanism, comprising rocking grate-bars, having fuel-supporting caps, inclined teeth projecting from the edges of the caps, the teeth at one end of each cap being lower than those at the other end, to permit of the lapping of the teeth of adjacent bars and means controlling the extent of movement of the bars, to preserve a space between the said lapping teeth.

60 9. A grate mechanism, comprising rocking bars having their meeting edges fitting upon each other and capable of riding one upon the other under the expansion of the bars and adjustable means upon the furnace-front for controlling the extent to which the spaces between the meeting edges of the bars are closed.

65 10. A grate mechanism, comprising rocking grate-bars having inclined lapping edges, rods connected with the said bars for rocking them, the said rods extending outside the furnace, levers for reciprocating said rods and adjustable stops for engaging said levers and limiting the extent of the movement of the bars toward each other.

70 11. A grate mechanism, comprising rocking bars having caps formed with edge teeth, said teeth having surfaces capable of fitting upon and lapping over the surface of the teeth of adjacent bars, means for rocking the bars and adjustable means on the furnace-front for limiting the movement of the bars when returned to their normal positions.

75 12. A grate mechanism, comprising rocking grate-bars having hollow body portions and removable fuel-supporting caps, the said caps being provided with laterally-extending webs, tie-bars at the edges of the caps and teeth projecting therefrom having inclined surfaces fitting one upon the other to facilitate the riding of the teeth of one bar upon those of the adjacent bar under the expansion of the caps.

80 13. A grate mechanism, comprising rocking bars, having removable fuel-engaging caps, the said caps being formed with shanks for engaging the body portions of the bars and laterally-extending webs having fuel-supporting teeth projecting therefrom, tie portions for strengthening the edges of the caps and teeth projecting from the tie portions and having inclined faces depressed below the upper surface of the caps and means for limiting the extent to which the said teeth of adjacent bars approach each other.

85 14. A grate mechanism, comprising rocking bars provided with fuel-engaging portions formed with edges arranged to lap upon the edges of adjacent bars, the said edges being depressed below the grate-surface to facilitate the use of a hoe upon the grate.

90 15. A grate mechanism, comprising a rock-

ing grate-bar having fuel-supporting caps and projecting teeth formed upon the edges of the caps capable of lapping upon the teeth of adjacent caps, the upper edges of said teeth being turned downwardly to form depressions between the grate-bars.

16. A grate mechanism comprising rocking grate-bars having inclined lapping edges, rods connected with said bars for rocking the

same, means outside of the furnace for reciprocating said rods and means for regulating the movement of said rods.

In testimony whereof I affix my signature in presence of two witnesses.

WILLIAM McCLAVE.
